WALTER A. SCHMIDT, OF LOS ANGELES, CALIFORNIA, ASSIGNOR TO INTERNATIONAL PRECIPITATION COMPANY, OF LOS ANGELES, CALIFORNIA, A CORPORATION OF CALIFORNIA.

METHOD AND MEANS FOR INDICATING SUSPENDED MATTER IN GASES.

1,168,227.

Specification of Letters Patent. Patented Jan. 11, 1916.

Application filed January 30, 1913. Serial No. 745,092.

To all whom it may concern:

Be it known that I, WALTER A. SCHMIDT, a citizen of the United States, residing at Los Angeles, in the county of Los Angeles and State of California, have invented a new and useful Method and Means for Indicating Suspended Matter in Gases, of which the following is a specification.

This invention relates to means for indicating the presence and amount of smoke, fumes, dust, mist, or other suspended matter in gases.

The invention is particularly applicable in connection with stacks or waste flues of furnaces and kilns, and the main object of the invention is to provide for indicating the amount of smoke or suspended matter in the gases passing in such stacks or flues.

I have discovered that an electrical discharge into air or gas is diminished or choked when suspended particles are brought into the path of the discharge, the choking effect increasing with the amount of suspended matter present. My invention is based on this discovery and consists essentially in means for passing an electrical discharge into or through the gas to be tested, and means for indicating the quantity or energy of the discharge.

The accompanying drawings illustrate embodiments of my invention, and referring thereto: Figure 1 is an elevation of a stack, partly broken away, showing the application of my invention thereto, the circuit connections being shown diagrammatically. Fig. 2 is a vertical section of the set of electrodes for the indicator. Fig. 3 is a vertical section of another form of the electrodes. Figs. 4 and 5 are elevations of other forms of the electrodes. Fig. 6 is a diagram of another form of the invention.

In Fig. 1, I have illustrated the application of my invention to a stack, chimney or flue, indicated at 1, for carrying off the waste gases from a furnace or kiln. Electrodes 2 and 3 are provided in the stack or flue, or near the outlet thereof, in such position that a part or all of the gas passing through the stack or flue is conducted between the electrodes. One, at least of such electrodes should be of a character to promote silent discharge of electricity therefrom through or into the gas. For this purpose, the electrode 2 may consist of a pointed rod

or wire, as shown in Fig. 2, the other electrode, 3, being in the form of a plate or sheet of conducting material. Electrodes 2 and 3 are connected to any suitable means for producing high tension electrical discharge from the electrode 2. Such means may consist of a step-up transformer 5, whose primary winding is connected to the wires 6 and 7 of an alternating current supply circuit, and whose secondary winding is connected to the wires 8 and 9, leading to the respective electrodes 2 and 3.

Suitable means are provided for measuring or indicating the magnitude of the discharge, for example, a millimeter 10 may be included in the energizing circuit for the transformer 5, to show the current being used in the apparatus, or a wattmeter 11 may be connected to this circuit to measure the energy consumed. By reading either or both of these instruments, an estimate may be made of the magnitude of the discharge. These instruments may be placed in the furnace room, office, or other location where information is desired as to the condition of the gases escaping through the stack or flue.

The operation of this embodiment of my invention, is as follows: Alternating current is supplied through the circuit 6, 7, to the transformer 5, causing a high tension alternating current to be produced in the secondary of said transformer, this current being delivered to the electrodes 2 and 3. If there is substantially no dust or other suspended matter in the gas between the electrodes, there will be a certain amount of discharge or passage of electricity from the electrodes into or through the gas between or adjacent to the electrodes, the amount of the discharge being dependent on the temperature of the gas, and the size and configuration of the electrode system. If now, dust or other suspended matter is introduced into the gas between the electrodes, the condition of the gas being otherwise unchanged, the suspended particles adjacent to the discharging electrode become charged similarly to that electrode, thereby reducing the potential gradient in the field adjacent to said electrode and correspondingly reducing or choking the discharge, the discharge being eventually reduced by an amount depending on the amount of suspended matter present,

so that by reading one or both of the instruments 10 and 11, and noting the decrease in reading, as compared with the reading for the condition, in which the gas is clear, an estimate may be made as to the amount of suspended matter present in the escaping gas. The charging of the suspended particles takes an appreciable time, so that with alternating current of ordinary frequency, there 10 may be more or less neutralization of the charges on the suspended particles by successive impulses, but by using instruments 10 or 11 of sufficient sensitiveness, the differential effect due to charging action may 15 be indicated with sufficient distinctness for the purpose of this invention. By using low frequency alternating current, the charging action and the resultant indication on the testing instrument may be increased. In 20 case the alternating current used is of such high frequency that a satisfactory indication is not obtained, a rectifier may be included in the circuit of the electrodes, as shown at 13 in Fig. 6. I prefer, however, 25 to dispense with the rectifier when possible, for the sake of simplicity, and ease, and economy of installation and operation of the apparatus.

In carrying out this invention it is essential, in order to produce the stated results, that the potential difference applied to the electrodes should be sufficient to produce a silent discharge, but not sufficient to produce a disruptive discharge or sparking, in 30 any material amount, between the electrodes, the operation as described depending on the variation of the silent discharge by reason of the presence of suspended matter.

Instead of a pointed electrode, a wire electrode 40 may be used for the discharging side, as indicated at 12 in Fig. 3, or any other suitable form of electrode may be used. As shown in Figs. 4 and 5, both of the electrodes may be adapted to produce or promote discharge, the electrodes being both pointed as at 2' in Fig. 4, or both formed of wire, as at 12', in Fig. 5. With such an arrangement the action above described takes place at each electrode.

50 What I claim is:

1. Means for indicating the amount of

suspended matter in gases, comprising electrodes, flue means inclosing said electrodes for directing a current of gas between the electrodes, a high tension electric circuit 55 connected to said electrodes and provided with means for applying high potential difference to said electrodes to produce silent discharge into the gas between the electrodes, and current indicating means responsive to the current in said high tension circuit, due to said silent discharge.

2. Means for indicating the amount of suspended matter in gases, comprising electrodes, means for directing a current of gas 65 between the electrodes, a high tension alternating current circuit connected to said electrodes to produce a silent discharge therebetween, a transformer having its secondary connected to said high tension 70 circuit, an alternating current supply circuit connected to the primary of said transformer, and a current indicating means in said supply circuit to indicate the amount of silent discharge between the electrodes. 75

3. The method of indicating the amount of suspended matter in gases, which consists in causing a current of such gases to pass between electrodes maintained at a high potential difference, sufficient to produce silent 80 discharge into the gas but not sufficient to produce disruptive discharge in material amount between the electrodes, and measuring the amount of such discharge.

4. The method of indicating the amount 85 of suspended matter in gases, which consists in causing the gas to pass between electrodes, applying to said electrodes high tension alternating electric potential difference, sufficient to cause silent discharge into 90 the gas between the electrodes, but not sufficient to cause disruptive discharge in material amount between the electrodes, and measuring the amount of such silent discharge. 95

In testimony whereof, I have hereunto set my hand at Los Angeles, California, this 24th day of January, 1913.

WALTER A. SCHMIDT.
